(57) **CLAIM**

The ornamental design for a football tee with three modes of use, as shown and described.

DESCRIPTION

FIG. 1 is a top perspective view of the football tee with three modes of use showing my new design;

FIG. 2 is a top plan view thereof;

FIG. 3 is a bottom plan view thereof;

FIG. 4 is a rear elevation view thereof;

FIG. 5 is a front elevation view thereof;

FIG. 6 is a right side elevation view thereof, the opposing left side view being a mirror image of the right side shown;

FIG. 7 is a bottom perspective view thereof; and,

FIG. 8 is an alternate bottom perspective view thereof.

The surfaces of the football tee herein are translucent, such that the features showing through the translucent surfaces in each of the figures correspond only to those whose outlines would be distinctly visible at the viewpoints shown. Oblique surface hatching has been omitted for the sake of visual clarity.
